(57) CLAIM

The ornamental design for a handbag, as shown and described.

DESCRIPTION

FIG. 1 is a front perspective view of a handbag showing my handbag design;

FIG. 2 is the front view of the handbag;

FIG. 3 is a top view of the handbag;

FIG. 4 is the rear view of the handbag;

FIG. 5 is a bottom view of the handbag;

FIG. 6 is a right-side view of the handbag; and,

FIG. 7 is a left-side view of the handbag.

The dashed line on FIGS. 1, 2, 4 indicates stitching and is part of the design.
